1**2,730,000****SLIDABLE JAW FACE MEANS FOR AN OPEN END WRENCH**

Harry E. Crittenden, Jr., Portsmouth, Va.

Application July 13, 1953, Serial No. 367,667

7 Claims. (Cl. 81—179)

The present invention relates to wrenches and more particularly to open end wrenches which operate with a ratchet character or quality.

The principal object of my invention is to provide an open end wrench which will tighten and loosen nuts or bolts without necessitating the removal of the wrench from the nut or bolt head at each turn or fraction of a turn. This present improvement also enables a mechanic to operate this wrench in close places because the open end allows a lateral approach to the nut or bolt head in contrast to an end or top approach and allows quick, smooth operation of a ratchet character.

A further object of this invention is to provide an open end "ratchet" wrench which is strong, and simple in construction and desirable which may be manufactured without complicated machining, specially made parts, assembly difficulties and undue changes in present manufacturing procedures.

With these objects in view this invention comprises the construction described hereinafter and illustrated in the accompanying drawings in which:

Fig. 1 is a side elevation partly in section of the wrench in "gripping" position.

Fig. 2 is a transverse section taken on the line 2—2 of Fig. 1 showing how the balls 6 and 13 extend through the walls to grip the nut or bolt head.

Fig. 3 is a side elevation showing the "ratchet" action in operation.

Fig. 4 is a fragmentary perspective view showing the open ended wrench head before the balls, springs and plugs are assembled therewith.

Figs. 5 and 6 are elevational views of the balls, springs and plugs in relative positions prior to assembly.

Referring to the drawings in detail my invention of the open end "ratchet" wrench comprises as shown in Fig. 1 the conventional handle 1, and bifurcated head 2, consisting of jaws 3 and 4. A hole 5, constituting a ball race or ball track, is drilled in the tip or open end side of jaw 3 deep enough to allow ball 6 to contact nut 7 at a point a fraction of an inch to the right of the central portion of jaw 3. Spring 9 is held in place by plug 10 to keep tension on the ball 6 holding said ball against bottom of the hole 5 for "gripping" position. Hole 12 is drilled in jaw 4 from the handle side deep enough for ball 13 to contact nut 7 at a point a fraction of an inch to the left of the central portion of jaw 4. Spring 14 is held in place by plug or cap 15 and keeps tension on ball 13, urging said ball against the bottom of the hole 12 for gripping position.

Fig. 2 shows how the holes or channels 5 and 12 are drilled off center to allow balls 6 and 13 to extend through inner portions of jaws 3 and 4. Since this type wrench may be manufactured for any size nut as is the conventional open end wrench, the distance between the jaws 3 and 4 equals the distance across the corners of any particular size nut or bolt head. The distance between balls 6 and 13 equals the distance across of opposite flats of the nut or bolt head in question. This means that each ball for any size wrench of this type must extend through its jaw one-half the difference between the distance across the corners and the distance across from flat to flat of any size nut in question. This allows equal pressure to be applied by each ball.

2

Fig. 3 is a side elevation, parts being moved to show balls 6 and 13 in ratchet position prior to gripping action.

In Fig. 1 when handle 1 is moved downward, as arrow indicates, the balls 6 and 13 will grip the nut at their points of contact and tend to loosen it. In Fig. 3 when handle 1 is moved upwardly without removing the wrench from the nut the corners of the nut would turn freely in the solid jaws 3 and 4, but would push ball 6 to the right and ball 13 to the left until the flats of the nut come into a position again parallel with the faces of the jaws 3 and 4. Radius curve 17, a part of the bifurcated head 2 and connecting jaws 3 and 4 would allow the nut to turn with a more smooth motion than a flat or V-shaped forged one. Springs 9 and 14 would push balls 6 and 13 back against the bottoms of their respective holes 5 and 12, thus making ready the next "gripping" position.

A number of necessary movements of the wrench in a back and forth motion without removing the wrench from the nut would produce a ratchet effect and loosen the nut completely. To tighten a nut, the wrench merely has to be reversed in position or turned on the opposite side so that the points of contact for balls 6 and 13 would be on opposite sides of central portions of the jaws. The same back and forth motion of the handle would tighten the nut.

This operation is not only quicker and easier than the conventional open end wrench but provides means for a mechanic to operate in close or narrow places where the removal of a wrench from a nut at every turn or fraction of a turn is avoided and the old retarded operation is eliminated.

Balls 6 and 13 are ordinary steel balls. The springs 9 and 14 do not serve in turning the nut except that they have enough tension to return the balls to the bottoms of their holes after each movement. The position of the point of contact when pressure is applied keeps the balls in gripping position. After the ratchet action has occurred, the spring merely returns the ball to gripping position. Caps or plugs 10 and 15 may be of proportionate thickness to the size of the wrench and may be hammered or pressed into place and then the open ends of the hole portions may be preened or upset over the plugs or caps to retain them securely in position.

In order to manufacture this movable ball grip wrench suitable stock must be selected and since, it is practically impossible to drill a hole or channel with one side open, the stock must have jaw material close enough to each other to provide for drilling holes in solid material. After the holes are drilled the opposed jaw faces are cut away to expose open sides of the drilled holes sufficiently so that the ball in each instance can protrude from the hole or channel to provide for the gripping action on a nut or bolt head.

Measurements and calculations must be made whereby lines may be scribed on the metal stock to properly locate the prospective drill holes.

The width of the wrench opening must substantially equal the distance across the nut from opposite corners thereof, so that the nut may rotate freely in one direction either clockwise or counter-clockwise depending upon the applied position of the wrench relative to the nut. The distance between the two balls is equal to the shortest distance between two opposed flats of the nut.

One half of the difference between the distances from one flat to an opposed flat and the distance between opposed corners of a nut, equals the distance a ball must protrude from its channel.

An example is afforded by the drawings of this application in which the nut operated upon is approximately three-fourths of an inch from one flat to its opposed flat. The nut shown is hexagonal. The balls 6 and 13 are located in contact with parallel planes which coincide

with those opposed flats, therefore the distances between said planes is approximately three-fourths of an inch. The distance between the jaws is approximately seven-eighths of an inch and is equal the distance from one corner of the nut to the opposed corner of the nut. The difference between seven-eighths and three-fourths is one-eighth. One half of one-eighth of an inch is one-sixteenth of an inch. One-sixteenth of an inch represents the approximate amount of protrusion of each ball from its jaw face.

The above formula can be used on any size hexagonal nut.

In order to choose a ball of proper size it is merely necessary to multiply the distance a ball protrudes from its jaw face, by four. Four times one-sixteenth equals one-fourth, therefore a one-fourth inch ball is required. The drilled holes should be slightly larger than one-fourth so that each ball can move freely in its channel.

It is noted that the balls do not contact the corner portions of the nuts but on the contrary engage the flats of the nuts at spaced distances from the corners. The use of applicant's wrench does not distort or wear away the corners of the nuts such as other known wrenches do by directly engaging the corners of the nuts.

Large and small wrenches may be manufactured since no complicated parts are necessary. Furthermore, an efficient wrench may be manufactured without the care and precision needed to manufacture similar wrenches.

Column 2, lines 17-25 explains how the wrench being used to loosen a nut may be turned over on opposite side to produce the tightening effect. The words "On" and "Off" could be stencilled or forged on the proper side to enable the mechanic to recognize by sight the correct approach whether to tighten or loosen as the need may be.

The paragraph at the top of page 4 explains the manufacturing and assembly of the caps 10 and 15. It may be noted that these caps or plugs could be the screw type plug, if the manufacturer thought advisable, but this would necessitate tapping the holes and threading the caps thus requiring another operation in manufacturing the wrench.

Column 3, lines 13-18 explains how to choose the correct size ball for the wrench to be used. In smaller wrenches, however, a ball measuring three times the distance the ball protrudes from its jaw face may be used.

Wrenches for square nuts may be manufactured provided all measurements are in their proper proportions.

Having fully described my invention what I claim is:

1. In a wrench, comprising a body having a handle terminating in a bifurcated flat head, said flat head comprising jaws having substantially parallel flat face portions opposed to each other, in combination with a pair of spring controlled contact balls, a pair of springs and means to maintain said springs and balls in operative position, each jaw having an elongated recessed portion therein to receive one of said balls and a spring plus means to retain each ball and spring in operative position within the major portion of said recessed portion, said recessed portions being reduced to provide opposed open sides whereby a minor portion of each ball may extend through the parallel jaw portions to engage a nut or bolt head of appropriate size, whereby each ball is adapted to engage directly the flat faces of the nut in a position adjacent the nearest corner of the nut relatively to said ball substantially as described.

2. In a wrench, comprising a body having a handle terminating in a bifurcated flat head, said flat head comprising jaws having substantially parallel flat face portions opposed to each other, in combination with a pair of spring controlled contact balls, a pair of springs and retaining means, whereby said balls and springs are retained in operative position, an elongated bored portion in each jaw to receive and retain, respectively, said balls, springs and retaining means, said bored portions being parallel to each other and having open sides arranged in

opposed relation to each other, whereby a minor portion of each of said balls may extend respectively through the opposed parallel face portions of said jaws into the path of a nut of appropriate size, whereby each ball is adapted to engage directly the flat faces of the nut in a position adjacent the nearest corner of the nut relatively to said ball substantially as described.

3. In a wrench, an elongated body terminating at one end in jaws, having substantially parallel flat faces arranged in spaced opposed relation to each other, in combination with a pair of spring controlled contact balls, a pair of springs and retaining means therefor, said jaws having parallel ball races therein to receive said balls and maintain a minor portion thereof exposed for contact with a nut of appropriate size, said balls races having permanently closed end portions, springs in said races to urge said balls toward the permanently closed ends of said races, the opposite ends of said races being closed by retaining means whereby said balls and springs are retained in operative relation relative to a nut of appropriate size within the jaws of the wrench, whereby each ball is adapted to engage directly the flat faces of the nut in a position adjacent the nearest corner of the nut relatively to said ball substantially as described.

4. The construction set forth in claim 3, in which one ball race extends inwardly from the outermost end of its jaw and the other ball race extends from the near ends of its jaw toward the remote end thereof.

5. In a wrench, comprising a body having a handle terminating in a bifurcated flat head, comprising a pair of jaws having a pair of parallel jaw faces, one of said jaws having a drilled portion extending from the open end side to receive a partly exposed steel ball, said ball being maintained in operative position by a helical spring and a plug located in said drilled portion, the said other jaw having a drilled portion extending from the handle side to receive a partly exposed similar ball, spring and plug, said spring and plug maintaining said similar ball in operative position.

6. In a wrench, comprising a body having a handle terminating in a bifurcated flat head comprising a pair of jaws, said jaws having opposed parallel flat faces, each face being provided with a ball race having a ball therein, each ball race having a bottom in combination with a spring and plug means in each race to maintain each ball, normally when the wrench is not in use, at the bottom of its race, said balls having a minor portion thereof extending from and through a portion of its race into and through said flat jaw faces, whereby said balls may contact the opposite flat faces of a nut at a position between the corners of the nut and also have the ratchet operating quality of a regular ratchet wrench.

7. In a wrench, comprising a body having a handle terminating in a bifurcated flat head, said flat head comprising jaws having substantially parallel flat face portions arranged in opposed relation to each other, balls, springs and plugs, said flat face portions of said jaws being each provided with a ball race to receive said ball, said spring and plug, said ball races having bottoms, said spring and plug maintaining its ball, normally when the wrench is not in use, at the bottom of its race, a minor portion of each ball extending through the side of its race and into the path between the flat face portions of said jaws, whereby said balls may contact the opposed flat faces of a nut at a position between the corners thereof and also have the ratchet operating quality of a regular ratchet wrench.
